(57) **CLAIM**

The ornamental design for a mule mug, substantially as shown and described.

DESCRIPTION

The patent or application file contains at least one drawing executed in color. Copies of this patent or patent application publication with color drawing will be provided by the Office upon request and payment of the necessary fee.

FIG. 1 is a front view of a mule mug, showing my new design;

FIG. 2 is a side view of the mug in FIG. 1;

FIG. 3 is a back view thereof;

FIG. 4 is a front perspective view thereof;

FIG. 5 is a bottom perspective view thereof; and,

FIG. 6 is a top perspective view thereof.
